UNITED STATES PATENT OFFICE.

GEORGE W. PROUTY, OF BOSTON, AND JASPER DERRY, OF MEDFORD, MASSACHUSETTS;
SAID DERRY ASSIGNOR TO ANDREW TERKELSEN, OF BOSTON, MASSACHUSETTS.

WRAPPING MACHINE.

Application filed May 9, 1923. Serial No. 637,657.

To all whom it may concern:

Be it known that we, GEORGE W. PROUTY and JASPER DERRY, citizens of the United States, residing at Boston, county of Suffolk, 5 State of Massachusetts, and at Medford, county of Middlesex, State of Massachusetts, respectively, have invented a certain new and useful Improvement in Wrapping Machines, of which the following is a specification, reference being had therein to the accompanying drawings.

This invention relates to wrapping machines of the general type shown and described in an application for Letters Patent 15 filed June 21, 1921, by George W. Prouty, Serial No. 479,410, and adapted primarily for wrapping annular objects, such as automobile tires, coils of wire, etc.

The present invention has for its object 20 to provide improved means whereby a machine of this type may be readily adjusted with minimum effort so as to adapt the same to the wrapping of articles of different sizes and for securely locking the parts in adjusted position against possibility of accidental displacement.

The foregoing and other objects of the invention, together with means whereby the same may be carried into effect, will best 30 be understood from the following description of one form or embodiment thereof illustrated in the accompanying drawings. It will be understood, however, that the particular construction described and shown 35 has been chosen for illustrative purposes merely, and that the invention, as defined by the claims hereunto appended, may be otherwise practised without departure from the spirit and scope thereof.

40 In said drawings—

Fig. 1 is a front elevation of the complete machine.

Fig. 2 is an enlarged section, taken substantially on the line 2, 2 of Figure 1, of the shuttle yoke lock.

Fig. 3 is a still further enlarged detail section taken substantially on the line 3, 3 of Figure 2.

The frame of the machine comprises a 50 base 15 and a curved yoke 16 which is pivotally mounted on a shaft 17 journalled in an upright 18 rising from said base. The yoke 16 is provided with guide rollers 19 for an annular shuttle 20 which is rotated 55 by a driving member in the form of a fric-

tion disk 21 secured to the shaft 17 and driven through connections (not shown herein) under the control of a starting treadle 22 from an electric motor 23. The tire or other work W to be wrapped is held by a weighted roller 14 upon work supporting rollers 24 (only one of which is shown in Fig. 1) which are driven through connections (not fully shown herein but generally indicated at 25) from the shaft 17, the arrangement being such that the work W will be turned relatively slowly with respect to the speed of rotation of the shuttle 20. Said shuttle is formed with a hinged segment 26 normally 60 closing a gap through which the work W may be inserted. The wrapping material, preferably in the form of a continuous strip S of paper, is supplied from a roll 30 supported by a reel or spindle 31 carried by the yoke 16. Said paper passes from the roll 30 over a tension device 32, thence through a folding device 33, and thence over a guide plate 34, to the shuttle 20. Said shuttle 20 comprises an annulus having on 65 one face a circular series of rollers 35 about which the strip S is wrapped when the shuttle is rotated, said strip being fed from the shuttle about a guide roller 36 to the work W. Between the shuttle 20 and the source of supply 30 there is provided a cutting mechanism comprising a knife 37 co-operating with a portion of the guide plate 34 to sever the strip S when a sufficient 70 length thereof has been wound around the shuttle rollers 35 to complete the wrapping of the work W. The knife 37 is automatically actuated, after a predetermined number of rotations of the driving disk 21, by a counting mechanism 38 actuated at each 75 rotation of said driving disk by a cam projection 39 thereon, said counting mechanism being manually adjustable in accordance with the size of the articles wrapped.

From the foregoing, the nature, location, and function of the parts referred to will be sufficiently understood for the purpose of the present case. With the exception of those hereinafter described, and in so far as the others enter into combination therewith, as pointed out in the claims, these parts are not involved in the present invention and may be of any suitable construction and arrangement.

In order to ensure the proper operation 110

of the machine, it is necessary that the shuttle 20 be centered with respect to the portion W' of the work W which passes therethrough. To this end a relative adjustment 5 of the shuttle and work is afforded by the pivotal mounting of the yoke 16 by which the shuttle is carried. Since said yoke is pivoted upon the shaft 17 which carries the driving disk 21, so that the axis of rotation 10 of said disk is the same as the pivotal axis of the yoke, this adjustment does not disturb the driving engagement of said disk with the shuttle.

The weight of the shuttle 20 and that 15 portion of the yoke 16 which supports the same is considerable, and, in order to facilitate the adjustment of the yoke, said weight is, in accordance with the present invention, partly counterbalanced by the paper roll 20 30 and adjacent parts, which are carried by the rear end of the yoke, or that portion thereof at the opposite side of the pivot 17 from that supporting the shuttle. In order further to support the weight of the shuttle 25 and the adjacent portion of the yoke, and force the latter upwardly, there is provided a spring 40 connected at its upper end to an ear 41 on the rear end of the yoke beyond the roll supporting spindle 31 and at its 30 lower end to a bracket 42 secured to the base 15. The yoke 16 is provided with a laterally or forwardly projecting handle 43 by means of which it may be raised and lowered about its pivot 17, this operation being 35 assisted by the spring 40 whose strength, in addition to the force exerted by the weight of the roll 30, is sufficient substantially to counterbalance the weight of the shuttle.

The yoke 16 is securely held in adjusted 40 position by means of a combined clamp and lock carried by an upright 44 rising from the base 15. The upright 44 has at its upper end an extension 45 (see particularly Fig. 2) bearing against one side face of the free forward end of the yoke, and at the opposite side face of the yoke is a plate 46 slidably connected with the upright 44 by dowel pins 47. The plate 46 is drawn toward the extension 45 or separated therefrom to clamp 45 and release the yoke by means of a screw 60 in threaded engagement with the plate 46 and having an unthreaded stem 48 passing through a slot 49 in the yoke 16 and a suitably disposed opening in the extension 45, said stem being provided with a handle 50 by means of which it may be turned. In addition to the clamp above described, means are provided for positively locking the yoke in its adjusted position, said locking 50 means comprising a latch 51 having an end adapted to engage any one of a series of recesses 52 in the yoke 16. Said latch 51 is withdrawn to disengage the yoke when the clamp is opened by means of a cam 53 secured as by a set screw 54, to the stem 48

between a head 61 on the latter and the extension 45, said cam having a surface which engages a shoulder 55 on said latch. Said latch is projected inwardly to engage the appropriate recess 52, when released by the 70 cam 53 upon turning of the stem 48 to tighten the clamp, by means of a spring pressed plunger 56 housed in said latch and engaging the inner face of the cam 53.

In order to adjust the yoke, the handle 50 75 is operated to turn the stem 48 and release the clamp, the cam 53 simultaneously withdrawing the latch 51. Said yoke is then raised or depressed by means of the handle 43, this operation being facilitated by the 80 spring 40, and the handle 50 then turned in the opposite direction to tighten the clamp, release the latch, and permit the end of the latter to engage a new recess 52 in the yoke.

Certain features shown and referred to 85 herein are covered by claims of other applications for Letters Patent as follows:—

As to the machine as a whole, application Serial No. 479,410, above referred to;

As to the driving mechanism, application 90 Serial No. 637,655, filed May 9, 1923, by George W. Prouty, Jasper Derry and Philip O. Tengberg;

As to the paper folder, Serial No. 637,656, 95 filed May 9, 1923, by George W. Prouty and Jasper Derry;

As to the shuttle, per se, and in combination with certain co-operating parts, Serial 100 No. 637,618, filed May 9, 1923, by Jasper Derry; and

As to the work supporting rollers and associated parts, Serial No. 637,658 filed May 9, 1923 by George W. Prouty.

Having thus described our invention, we 105 claim:—

1. In a machine of the class described, a work support, an annular shuttle through which the work is adapted to be moved, a curved yoke mounted to swing about a fixed pivot, rotatable members thereon to support said shuttle, a shuttle driving member rotatable about the axis of said pivot, a spring for forcing said yoke upwardly about its pivot, and means for locking said yoke in 110 adjusted position.

2. In a machine of the class described, a work support, an annular shuttle through which the work is adapted to be moved, a curved yoke mounted to swing about a fixed pivot, rotatable members thereon to support said shuttle, a shuttle driving member rotatable about the axis of said pivot, a spring for forcing said yoke upwardly about its pivot, and clamping members on opposite sides of said yoke for retaining it in adjusted 115 position.

3. In a machine of the class described, a work support, an annular shuttle through which the work is adapted to be moved, a curved yoke mounted to swing about a fixed 120

- pivot, rotatable members thereon to support said shuttle, a shuttle driving member rotatable about the axis of said pivot, a spring for forcing said yoke upwardly about its pivot, a bracket having an extension bearing against a side face of said yoke, a plate on the opposite side face of said yoke, and a rotatable member extending through said bracket and having an end threaded to said 5 plate whereby the latter may be moved toward said extension and clamp the yoke in its adjusted position.
4. In a machine of the class described, a work support, an annular shuttle through 15 which the work is adapted to be moved, a curved yoke mounted to swing about a fixed pivot, rotatable members thereon to support said shuttle, a shuttle driving member rotatable about the axis of said pivot, a spring 20 for forcing said yoke upwardly about its pivot, means for clamping said yoke in adjusted position, and a laterally projecting handle at the free end of said yoke whereby 25 said yoke when unclamped may be forced downwardly against the tension of said spring.
5. In a machine of the class described, a work support, an annular shuttle through which the work is adapted to be moved, a 30 curved yoke mounted to swing about a fixed pivot, rotatable members thereon to support said shuttle, means for driving said shuttle about its center, a resilient member for forcing said yoke upwardly about its pivot, and 35 means for locking said yoke in adjusted position.
6. In a machine of the class described, a base, a work support thereon, a rotatable annular shuttle through which the work is 40 adapted to be moved, a yoke pivotally mounted above said base and supporting said shuttle at one side of its pivot, and a spring connecting said yoke at the other side of its pivot with said base.
- 45 7. In a machine of the class described, a work support, an annular shuttle movable about its center and through which the work is adapted to be moved, a pivoted support for said shuttle, and means mounted upon 50 the shuttle support for supporting a supply of wrapping material in a continuous strip adapted to be fed to said shuttle.
- 55 8. In a machine of the character described, a work support, a rotatable annular shuttle through which the work is adapted to be moved, a pivoted yoke supporting said shuttle at one side of its pivot, and a support for a supply of wrapping material mounted
- upon said yoke at the opposite side of its pivot.
9. In a machine of the character described, a work support, a rotatable annular shuttle through which the work is adapted to be moved, a pivoted yoke supporting said shuttle at one side of its pivot, a support for a 65 supply of wrapping material mounted upon said yoke at the opposite side of its pivot, and additional means for counterbalancing said yoke and shuttle.
10. In a machine of the character described, a work support, a rotatable annular shuttle through which the work is adapted to be moved, a pivoted shuttle supporting yoke, and a latch for positively locking said 70 yoke in adjusted position about its pivot.
11. In a machine of the character described, a work support, a rotatable annular shuttle through which the work is adapted to be moved, a pivoted shuttle supporting yoke, a clamp for holding said yoke in 75 adjusted position about its pivot, and a latch for positively locking said yoke.
12. In a machine of the character described, a work support, a rotatable annular shuttle through which the work is adapted to be moved, a pivoted shuttle supporting yoke, a spring pressed latch for positively locking said yoke in adjusted position about 80 its pivot, and a cam for releasing said latch.
13. In a machine of the character described, a work support, a rotatable annular shuttle through which the work is adapted to be moved, a pivoted shuttle supporting yoke, a clamp for holding said yoke in 85 adjusted position about its pivot, a screw for operating said clamp, a spring pressed latch for positively locking said yoke, and a cam carried by said screw for releasing said latch.
14. In a machine of the character described, a work support, a rotatable annular shuttle through which the work is adapted to be moved, a pivoted shuttle supporting yoke, a clamp for holding said yoke in 90 adjusted position about its pivot, a screw for operating said clamp, a latch for positively locking said yoke, a cam carried by said screw for releasing said latch, and a spring device housed in said latch and engaging said cam for moving said latch into locking 95 engagement with said yoke when permitted by said cam.
- In testimony whereof we affix our signatures.

GEORGE W. PROUTY.
JASPER DERRY.
